(57) **CLAIM**

The ornamental design for a demolition hammer, as shown and described.

DESCRIPTION

FIG. 1 is a rear perspective view of a demolition hammer in accordance with an embodiment of the present invention; FIG. 2 is a front perspective view of the demolition hammer of FIG. 1;

FIG. 3 is a right side elevational view of the demolition hammer of FIG. 1, the left side elevational view being a mirror image thereof;

FIG. 4 is a top plan view of the demolition hammer of FIG. 1;

FIG. 5 is a bottom plan view of the demolition hammer of FIG. 1;

FIG. 6 is a front elevational view of the demolition hammer of the FIG. 1; and,

FIG. 7 is a rear elevational view of the demolition hammer of the FIG. 1.
